FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side thereof;

FIG. 9 is a front perspective view of the flexible display device of FIG. 1 in a folded state;

FIG. 10 is a rear perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof;

FIG. 16 is a right side view thereof;

FIG. 17 is a front perspective view of a second embodiment of a flexible display device in an unfolded state showing the claimed design;

FIG. 18 is a rear perspective view thereof;

FIG. 19 is a front view thereof;

FIG. 20 is a rear view thereof;

FIG. 21 is a top view thereof;

FIG. 22 is a bottom view thereof;

FIG. 23 is a left side view thereof;

FIG. 24 is a right side thereof;

FIG. 25 is a front perspective view of the flexible display device of FIG. 17 in a folded state;

FIG. 26 is a rear perspective view thereof;

FIG. 27 is a front view thereof;

FIG. 28 is a rear view thereof;

FIG. 29 is a top view thereof;

FIG. 30 is a bottom view thereof;

FIG. 31 is a left side view thereof;

FIG. 32 is a right side view thereof;

FIG. 33 is a front perspective view of a third embodiment of a flexible display device in an unfolded state showing the claimed design;

FIG. 34 is a rear perspective view thereof;

(Continued)

FIG. 35 is a front view thereof;
 FIG. 36 is a rear view thereof;
 FIG. 37 is a top view thereof;
 FIG. 38 is a bottom view thereof;
